UNITED STATES PATENT OFFICE

ARBA G. WILLIAMSON, OF CARNEGIE, PENNSYLVANIA, ASSIGNOR, BY MESNE ASSIGNMENTS, TO THE UNION SWITCH & SIGNAL COMPANY, OF SWISSVALE, PENNSYLVANIA, A CORPORATION OF PENNSYLVANIA

TRAIN-CONTROL SYSTEM

Application filed March 3, 1927, Serial No. 172,325. Renewed November 19, 1929.

This invention relates generally to train control and track way circuit systems, and has for its main object and feature the provision of simple means whereby at least three 5 indications may be transmitted from track-way elements, preferably the traffic rails, fed by a power source supplying a single frequency current.

In the accompanying drawings the invention is shown in several concrete and preferred forms in which:

Fig. 1 is a diagrammatic view of a track circuit embodying one form of the invention.

15 Fig. 2 is a diagrammatic view of one form of the train carried apparatus, showing the use of rectifying detectors.

Fig. 3 is a view similar to Fig. 2 showing the use of amplifiers.

20 Fig. 4 is a diagrammatic view showing a second form of track apparatus.

Fig. 5 is a diagrammatic view showing a modified form of the invention of Figs. 1 and 4.

25 Fig. 6 is a diagrammatic view showing a still further modified form of the invention in which two track circuits are employed.

Fig. 7 shows a diagrammatic view of both 30 train and track equipment of a modified form of the invention.

Figs. 8 and 9 are diagrammatic views showing the different pronounced harmonic components of a non-sinusoidal alternating current.

35 Fig. 10 is a diagrammatic view of a magnetization curve showing the saturation point.

Fig. 11 is a diagrammatic view showing a 40 modification of the construction disclosed in Fig. 7.

Fig. 12 is a sectional detail view of a valve construction that may be used in connection with the invention.

The apparatus shown in Figure 5 has been 45 made the subject matter of a divisional application, Serial No. 508,618, filed Jan. 14, 1931, for track circuit systems, containing claims specific to this view.

In this invention it is proposed to make 50 use of the fact that the wave form of a single-

frequency alternating current can be made non-sinusoidal; that is: the alternating current can be so modified that the momentary values of a compound resultant wave do not vary in accordance with a pure sine law, but 55 has momentary values which are the summation of the sine functions of the waves of several components. The sine function possessing the lowest frequency is called the first harmonic component or the fundamental, and 60 all the other sine functions, whose frequencies are multiples of that of the fundamental, are called higher or upper harmonic components. This is illustrated in the diagram, Fig. 8 which shows one cycle of a single-frequency 65 alternating current wave in which the horizontal axis represents time and the vertical axis represents the current flow. It will be seen from this that the compound resultant 70 wave has an amplitude, at any point, which is the summation of the amplitudes of the several harmonic components. The harmonic components shown in Fig. 8 are the first, or fundamental, the third and the seventh, and 75 it will be understood that one or more such pronounced harmonic components may be utilized, by properly tuning pick-up circuits on the train, to give various indications on the train to control suitable indicating means such as signals or brake setting means or 80 both.

A track way arrangement embodying the invention in one form is shown in Fig. 1 in which the track elements are traffic rails 1 and 2 over which traffic moves in the direction of the arrow, said rails being preferably arranged in blocks A, B and C by means of insulated joints 3 or otherwise. Referring particularly to block B, a power source to supply a single frequency current is shown 85 and this may be generator G which, in that event, could be connected directly by suitable leads to rails 1 and 2 of each block, but, preferably, generator G supplies power to line wires 12 and 13 and they in turn deliver 90 current to the rails by means of transformer Tb which supply the rails directly. The point that we are making is that either generator G or transformer Tb may be considered the power source. Transformer Tb is 100

here of the type having a closed iron core so that by proper designing of the iron magnetic path the working point of the magnetization curve will be at the point X, 5 Fig. 10, in consequence of which secondary 4 becomes a source of alternating voltage supplying alternating current of non-sinusoidal form and having pronounced harmonic components. A probable explanation of this 10 phenomenon is that there is a lack of uniformity of the magnetic field of the iron constituting the magnetic path of generators and transformers, and this is illustrated in Fig. 10 which shows a typical magnetization curve 15 for iron. Let us suppose that the magnetization of the iron has been brought to point X. If now, by means of an additional alternating magnetization force, equal increments and decrements be added, the magnetization will 20 increase during the positive half of the cycle by the small amount $e-f$, while, during the negative half of the cycle, magnetic induction will decrease by a considerably larger amount $x-d$. Such an asymmetrical condition gives rise to pronounced higher harmonic components, the third harmonic component being particularly prominent.

Referring to Fig. 1, one side of secondary 4 is connected to rail 1 by wire 5, and rail 2 30 is connected to the opposite terminal of secondary 4 by wire 6, ohmic resistance 7, wire 8, front contact 9 of track relay Ra for block A in advance and wire 10. Rail 2 may also be connected to secondary 4 by wire 6, impedance 35 coil 11, wire 14, back contact 15 of relay Ra and wire 10. Impedance coil 11 is so designed that it has a high inductive reactance compared to its ohmic resistance. At the ingoing end of block B in Fig. 1 track relay Rb is connected to the rails by wires 16 and 17. It 40 will now be seen that normally, current flows from secondary 4 along, let us say, wire 5, rail 1, wire 16, coil of relay Rb, wire 17, rail 2, wire 6, ohmic resistance 7, wire 8, front 45 contact 9 and wire 10 and back to secondary 4. If relay Ra is deenergized the return from rail 2 will be over wire 6, impedance coil 11, back contact 15, wire 10 and secondary 4. The track relay, such as Rb, is an alternating current relay of the type that does not depend 50 for its operation upon any particular wave form of alternating current and will therefore function in the same way whether ohmic resistance 7 or impedance coil 11 is in the circuit; provided, of course that the values 55 of 7 and 11 are such that the mean effective value of the current flowing in Rb is the same with either 7 or 11 in circuit.

The effect, upon the current flowing in the 60 rails, by cutting 7 and 11 in and out is as follows: When ohmic resistance 7 is in circuit, and the load on secondary 4 is largely non-inductive, then current flowing in the rails will have a pronounced third harmonic component in addition to a pronounced first har-

monic component (or fundamental); that is, disregarding the seventh pronounced harmonic component shown in Fig. 8, the resultant curve will be more or less like the one in that figure. But when impedance coil 11 is in circuit the load on secondary 4 becomes largely inductive and this will tend to suppress or filter out the pronounced third harmonic component thereby leaving but a single pronounced harmonic component, in this instance the fundamental, and the wave curve will then be substantially as shown in Fig. 9.

The probable explanation of this phenomenon is as follows: There is both a voltage curve and a current curve and if the circuit contains only ohmic resistance the current curve will have substantially the same shape as the voltage curve. On the other hand, if the circuit contains largely inductive resistance the current curve will approximate more closely a pure sine wave than will the voltage curve, this being due to the fact that inductive reactance is proportional to frequency and thus greater in value for the higher harmonic components and it therefore tends to suppress the higher harmonic components of the resultant wave more than it tends to suppress the fundamental or first harmonic component. Again, should the circuit contain capacity, then the higher harmonic components may be more prominent in the current curve than in the voltage curve. It will therefore be understood that resistance element 7 is not a necessary part of the invention. It is placed in the drawing largely to illustrate the character of the circuit. It does, however, possess a real function in preventing the current from being dissipated when impedance coil 11 is not in circuit.

In the illustrative form of the invention described thus far it will be understood that all the blocks of the system are equipped in the manner described in connection with block B. The track way arrangement, in the present form, is therefore that when block A is unoccupied and relay Ra is energized a non-sinusoidal single-frequency alternating current will flow in the rails of block B and this current will be characterized by two pronounced harmonic components, here the first and the third components. When block A is occupied and relay Ra is deenergized then the current in the rails of block B will have a single pronounced harmonic component, here the fundamental, and a very small, if any, third harmonic component. If a second train enters a block already occupied then such second train will receive no current, due to the shunting action of the wheels and axles of the train in advance. We thus establish three traffic conditions with a single alternating current, a great simplification over systems now used. The track way arrangement shown has another advantage in that it is not necessary to have a separate

track circuit to energize the track relay, this function being performed by the same current as that which energizes the means on the train. It will also be understood that wayside signals of the three position type can be operated and controlled by a track way circuit of this type by having two track relays, one responsive to one pronounced harmonic component and the other to another pronounced harmonic component.

- Any suitable train equipment responsive to the different pronounced harmonic components, or their absence, may be employed. Fig. 2 shows a rather complex form embodying both signals and brake-setting means, in which 20 and 21 indicate two pick-up coils carried by the train or vehicle, said coils being in inductive relation, or otherwise, to current flowing in the track. These coils are connected in series in such a manner that voltage induced in them by current flowing in opposite directions in the traffic rails will be additive, and are further connected in a circuit including wires 22, 23, 25 and 27 as well as primaries 24 and 26 of transformers T and T'. Said transformers are alike and are of the type commonly used in this class of work, their primary windings having a high impedance. E and E' represent two rectifying detectors of the electron tube type containing here three elements, a filament, a grid and a plate. The grid circuit of tube E is as follows: secondary 28 of transformer T, wire 29, condenser 18, wire 19, grid 32, filament 33, wire 34 and back to secondary 28. Tuning condenser 35 bridges this circuit by means of wires 36 and 37, and, in this instance, condenser 35 is so chosen that the circuit is tuned to resonance with the fundamental or first pronounced harmonic component of the track circuit current. The grid circuit of tube E' is as follows: secondary 38 of transformer T', wire 39, condenser 40, wire 41, grid 42, filament 43, wire 44 and back to secondary 38. Tuning condenser 45 bridges the circuit by means of wires 46 and 47, and, in this instance, condenser 45 is so chosen that the circuit is tuned to resonance with the third pronounced harmonic component of the track circuit current.
- Generator G', of the train equipment, is driven by any suitable means, such as a steam turbine, not shown, and delivers a voltage that drives motor M' of motor generator MG. The generator end of the motor generator is supplied with two commutators G² and G³, the former furnishing a voltage suitable for the filament circuit of E and E', and the latter a voltage suitable for the plate circuits of tubes E and E'. The filament circuit consists of commutator G², wire 48, filament 43 of tube E', wires 44, 49 and 34, filament 33 of tube E and wire 50 back to G². The plate circuit for tube E consists of commutator G³, wire 51, coil of relay R, wire

52, plate 53 of tube E, filament 33 and wires 50 and 54 back to commutator G³. The plate circuit of tube E' consists of: commutator G³, wires 51 and 55, coil of relay R', wire 56, plate 57 of tube E', filament 43, wires 44, 49 and 34, filament 33 of tube E, and wires 50 and 54 back to G³.

By the foregoing means the grid circuit of tube E is responsive to the influence of one pronounced harmonic component and the grid circuit of tube E' is responsive to the influence of another pronounced harmonic component of the track way current.

The effect of each of these pronounced harmonic components is to render the grid, complementary thereto, negative with respect to the filament so long as the appropriate current flows in the track way. If the original value of the plate circuit current is assumed to be 1.00 when no current is flowing in the grid circuit, then, when the grid is rendered negative by the induced voltage in the grid circuit, the plate circuit current is choked down to say 0.40 after the manner described in detail in application Ser. No. 147,403, filed November 10, 1926; that is, an intermediate value of plate circuit current is established so long as the appropriate current flow is present in the rails.

Relays R and R' are alike and are here of the direct current polarized type. Each relay is provided with a single polarized armature which is so biased by air gap adjustments and strength of magnetic poles that it will take one position (right hand position in Fig. 2) when current of the proper polarity and of a given value (here 0.40) is flowing in the coils of the relay, but, if the current value of the plate circuit is either increased or decreased or fails totally, then the polarized armature will be forced to another position (in Fig. 2 the left hand position).

The indicating means used may be of any suitable character and may be merely an indicator such as I having three differently colored lights and these lights receive, in this instance, power direct from generator G'. The proceed indication light circuit is as follows: generator G', wires 58 and 59, armature 30 of relay R, contact point 31, connection 60, armature 66 of relay R', contact point 61, wire 62, light 63 and wires 64 and 65 back to generator G'. The caution light circuit is as follows: generator G', wires 58 and 59, armature 30, contact point 31, connection 60, armature 66, contact point 67, wire 68, light 69 and wires 67', 64 and 65 back to generator G'. The danger indication light circuit is as follows: generator G', wires 58 and 59, armature 30, contact point 93, wire 70, light 71 and wires 72, 64 and 65 back to generator G'.

When a train enters an unoccupied block B from the right, and block A is likewise

100

105

110

115

120

125

130

unoccupied, then the wheels and axles of the train will shunt the current from track relay R_b , and the track circuit current for block B there being only ohmic resistance in said circuit (graphically indicated by element 7) will have two pronounced harmonic components, and this current will be picked up by coils 20 and 21. Each of the grid circuits of tubes E and E' will respond to its proper pronounced harmonic component and the grids of both tubes will be rendered negative with the result that the plate circuit current of each tube will be choked down to an intermediate value of say 0.40 and consequently armatures 30 and 66 will both occupy the right-hand position shown in Fig. 2. This will close the proceed indication circuit previously described. If block A were occupied when the train entered block B then track relay R_a would be deenergized and the current supplied to the track rails would pass through impedance coil 11 and this would eliminate, or at least greatly minimize, or render ineffective, the third pronounced harmonic component and therefore the grid of tube E' would no longer remain negative. Consequently the value of the current in the plate circuit would rise to 1.00, armature 66 would move to the left hand position and the circuit previously described through light 69 would be established. The grid of tube E would remain negative in response to the current having the first predominant harmonic component. Again, should block B be occupied when a train enters said block, then all current from secondary 4 will be shunted away from the second train and the grid of neither tube would be negative and consequently the value of the current in both plate circuits would rise to 1.00 and both armatures 30 and 66 would be moved to the left hand positions with the result that the circuit previously described through danger light 71 would be established. It will also be understood that should a wire break in either of the plate circuits or the source of power fail then either or both armatures 30 and 66 would move to the left hand position. The train-carried apparatus can of course be made as elaborate as desired and may include both brake setting means and multiple speed control means in accordance with the requirements of the system on which it is used. In Fig. 2 there happens to be shown, in addition to indicator I, brake setting means designated by three magnet valves M, M' and M'', the coils of which are connected in parallel respectively with the proceed, caution and danger indication lights. The circuit for valve M branches off wire 62, and then passes over wire 73, coil of M, and wire 74 back to wire 65. The circuit for valve M' branches off wire 68 and then passes over wire 75, coil of M' and by wire 76 back to wire 65. The circuit for M'' branches off wire 70 and

then passes over wire 77, coil of M'', wire 78 and back to wire 65. In Fig. 12 is shown a detail view of the valve structure, which, however, may be varied widely. BV indicates a brake valve which in its normal position has port 131 closed and port 125 open. Under these circumstances, pressure can flow from the brake pipe to the engineer's valve but cannot flow to exhaust port 131'. The brake valve is maintained in this position by pressure under piston 130 but when this pressure fails port 125 is closed and port 131 is opened thereby connecting the brake pipe with exhaust port 131'. Pressure is maintained under piston 130 by the three magnet valves M, M' and M'' the valve ports of which are connected in series with each other, and are connected at one end with the cylinder containing piston 130 and at the other end with an exhaust 131''. When valve M is energized port 126 is closed and valve 124 opened and pressure can then flow from the main reservoir past valve 124 to piston 130. So likewise when either valve M' or M'' is energized pressure will flow past the respective valves 124' or 124 to sustain piston 130, but if all three valves become deenergized and the supply valves 124, 124' and 124 are all closed the piston 130 will force the pressure past ports 126, 126' and 127 to exhaust 131'' and ports 131 and 131' will be open and port 125 will be closed, thereby applying the brakes. Each of the magnet valves is so constructed that when it becomes deenergized its armature such as 123', 128 or 128' falls so far down that it will not be lifted when the magnet is reenergized. The engineer should therefore acknowledge each indication by lifting a plunger such as 122', 129 or 129' manually to thereby restore the armature.

In Fig. 3 is shown a second embodiment of the invention in which electron tubes E and E' are used as amplifiers and relays R and R' are alternating current relays. In this form of the invention two pairs of pick-up coils are used, 80 and 81 being connected to the grid-filament circuit of tube E and coils 83 and 84 being connected to the grid-filament circuit of tube E'. Condensers 82 and 85 span the respective grid-filament circuits to tune the two circuits to resonance of the two pronounced harmonic components. In this instance the grids of the tubes are not rendered negative but an alternating component is impressed upon each plate circuit and each relay R and R' responds to the influence of the proper pronounced harmonic component in the track circuit. The track circuit shown in Fig. 1 can be used in connection with this train equipment, and the general method of operation will be the same as that previously described in connection with Figs. 1 and 2.

In Fig. 4 is shown a modified form of track circuit construction in which, when the track

relay of the block in advance is energized, a shunt path is closed around impedance coil 86 and which shunt path includes the condenser 87. This condenser is given such value that it counteracts the inductive reactance of coil 86 so that the apparent resistance offered to the track circuit current is that of ohmic resistance. Under these conditions the track current will have two pronounced harmonic components, the first and the third. When the track relay of the block in advance is deenergized then impedance coil 86 is placed in circuit and the third harmonic component of the track current will be suppressed. The construction shown in Fig. 4 can be associated with the construction shown in either Fig. 2 or 3.

In Fig. 5 is shown another modification of the track circuit. Here transformer T_b is provided with a coil 250 on its iron core and this coil is energized by battery 251 by means of a circuit which is closed when track relay R_a of the block in advance is energized. When 250 energizes the core of T_b , the working point of said core is well upon the curve, say at point X of Fig. 10, and consequently, during the positive half of the cycle of the alternating current the induction will increase but slightly while during the negative half of the cycle the decrease will be relatively large. This uneven change in the induction of the iron core will produce a wave form in the current of the secondary 4 of transformer T_b which will have a pronounced third harmonic component as well as a pronounced first harmonic component. When relay R_a is deenergized and coil 250 thereby also becomes deenergized then the working point on the magnetization curve is well down below the knee of the curve and the pronounced third harmonic component is suppressed. The result is therefore the same as in Figs. 1 and 4.

In Fig. 6 is shown still another modification of the invention in which two track circuits are used. As there shown, secondary 4 of transformer T_b is connected, at the outgoing end of the block, to rails 1 and 2 to which latter, at the incoming end of the block, is connected the usual track relay, the rails being in series. Inasmuch as this circuit contains merely ohmic resistance the current flow in the rails will have, let us say, a pronounced third harmonic component. 200 indicates another secondary of transformer T_b which supplies power to a circuit as follows: wire 201, contact 202, armature 203 of the track relay of the block in advance, wire 204, center tap 205, rails 1 and 2 in parallel, center tap 206, wire 207 and back to secondary 200. Inasmuch as the resistance of this circuit is largely non-inductive the current flowing therein will have pronounced higher harmonic components, let us say notably the third harmonic component. Pick-up coils 210 and 211 for train 212 are so connected that

the voltage induced in them by the current supplied by secondary 4 to the rails in series will be additive, and the pick-up circuit is tuned to resonance at the frequency of the third harmonic component. This pick-up circuit is connected to the grid circuit of tube E (Fig. 2) in the same manner as in that figure and will therefore control relay R of Fig. 2 in the way previously described. Pick-up coils 213 and 214 of train 212 are so connected that voltage induced therein by current flowing in parallel in the rails will be additive, and the pick-up circuit is tuned to resonance at the frequency of the third harmonic component. The pick-up circuit when connected to the grid of tube E' (Fig. 2) in the manner previously described can be used to control relay R' in the way previously set forth. When current is flowing in the rails in both the series and the parallel circuits a proceed indication is established, but when the track relay of the block in advance is deenergized the parallel circuit fed by secondary 200 is ruptured and current only in the series circuit is flowing. This establishes a caution indication. If the series circuit current is absent a danger indication is established. The advantage of this particular form of the invention, in which both pick-up circuits are responsive to higher harmonic components is that this system is not subject to the influence of stray currents.

The system is not limited to three indications. Obviously two indications, or even one indication can be used as will be apparent from Fig. 6. So also a number of indications greater than three can be employed, since this may be desirable when short blocks are used and the speed of certain classes of trains is high.

In Fig. 7 a system having more than three indications is shown. When four indications are desired an additional tube E'' is employed and also an additional coordinating relay R'' with the necessary grid, plate and filament circuits. However, as this additional equipment is largely a repetition of what has been described in connection with tubes E and E' it is thought to be unnecessary to repeat the description thereof. In Fig. 7 we have chosen to use the tubes as rectifying detectors but it will be understood from Fig. 3 that the tubes may be used as amplifiers. In Fig. 7 the indicating means employed happen to be a magnet valve M the controlling circuit of which passes through a multiple speed control device comprising a contact arm 226 moved by rod 225 actuated by a suitable governor such as a fly-ball governor geared to the train. Four segments are employed 227, 228, 229 and 230 with which the contact arm engages and these segments are of different lengths to thereby impose different speed limits on the train under different traffic conditions in a manner well

understood. The track circuit arrangement shown in Fig. 7 is a modification of that shown in Fig. 6 in that a line relay 215 is employed at each block together with a controlling circuit for this relay 215. Associated with transformer T_b is a secondary 216 connected in a circuit as follows: wire 217, armature 218 of the track relay of block A, contact point 219, wire 220, coil of relay 215 of block B and then by a common return wire indicated at c back to secondary 216. That track circuit of block C which includes the two rails in parallel is then controlled through a contact of line relay 215 in such a way that when relay 215 is energized then the parallel track circuit passes through non-inductive resistance 221 and front contact 222, whereas when relay 215 is deenergized then said parallel circuit includes inductive reactance 224 and back contact 223. Therefore each block is provided with a series-rail circuit current having a plurality of pronounced harmonic components, here the first and third, and with a parallel-rail circuit current also having a plurality of pronounced harmonic components, here the first and third, and it will be understood that this is the condition of a block as C when two blocks in advance, say A and B are unoccupied. When block A is occupied then we have in block C a series-rail current as before but the parallel-rail current will have only one pronounced harmonic component, the third harmonic component being suppressed owing to the inclusion of inductive reactance 224 in the parallel circuit. Again if block B is occupied then there will be no parallel-rail current at all in block C owing to the opening of contact 231 of the track relay of block B. Should block C be occupied when a second train enters the block C, then the second train will receive no current at all. The pick-up coils on the train associated with tube E are connected to respond to the series-rail current, and the pick-up circuit associated therewith is tuned to proper resonance at the frequency of one of the harmonic components of this current—preferably the higher harmonic component. The other pair of coils in the train is connected to respond to the parallel-rail current and the grid circuit of tube E' is tuned to resonance at the frequency of the first harmonic component while the grid circuit of tube E'' is tuned to resonance with the third harmonic component of said parallel-rail circuit current. Therefore, when a train enters a block, and the next two blocks in advance are unoccupied all three tubes E , E' and E'' are influenced and relays R, R' and R'' will hold their armatures in the right hand positions and the maximum speed will be permitted. If the second block in advance is occupied and the first block in advance is unoccupied then tubes E and E' are influenced and relays R and R' will hold

their armatures in the right hand positions, but tube E'' will not be influenced and relay R'' will hold its armature in the left hand position thus permitting the train to proceed at the second speed. If the first block in advance is occupied then tube E only is influenced and only relay R will hold its armature in the right hand position, the armatures of relays R' and R'' being in the left hand positions, thus permitting the train to proceed at a still lower speed. If the block is already occupied when the second train enters then all three relays R, R' and R'' will move their armatures to the left hand positions and the train can proceed only at the lowest speed. 70 75 80

In Fig. 11 is shown a modification of the form of the invention shown in Fig. 7. Here each block is provided with a two-element A. C. polarized relay such as R_a so constructed that when a block is supplied with current of one relative polarity from a secondary such as 4 the corresponding track relay will hold armatures 252, 253 and 254 in the right hand positions, will hold said armatures in the left hand positions if current of reverse relative polarity is applied, and when a track relay is deenergized the corresponding armatures will occupy the mid-positions. Each track transformer, of which T_b is an example, is provided with a secondary 255 that supplies power to the local element of the corresponding track relay, and associated with each transformer is a coil 250 to increase the magnetization of the iron core of the transformer to near the saturation point so that, whenever coil 250 is energized by battery 251, the current delivered by secondary 4 will have pronounced higher harmonic components. The circuit for coil 250 and battery 251 passes through the right and left hand contacts of the track relay R_a , and said coil 250 will therefore be energized whenever the track winding of a relay, as R_a , is energized regardless of the relative polarity of the energizing current. Each block is provided with two filters 256 and 257, filter 256 being composed of inductance 258 and capacity 259 arranged in parallel, and the values of these elements are so chosen that the filter is resonant to the seventh harmonic component of current supplied by secondary 4 and will readily pass it while the other harmonic components, except the first, will be suppressed. Filter 257 is composed of inductance 260 and capacity 261 in parallel and their values are so chosen that it is resonant to the third harmonic component of current delivered by secondary 4 and will readily pass it while the other harmonic components, except the first, will be suppressed. When, therefore, the armatures of relay R_a occupy the right hand positions a current will flow in the rails having two pronounced harmonic components, here the first and seventh, and when said armatures 90 95 100 105 110 115 120 125 130

occupy the left hand positions a current will flow in the rails having two pronounced harmonic components, here the first and third. When the armatures occupy the mid-positions the current in the rails will have only the first harmonic component. These three conditions correspond to three different traffic conditions, the fourth being total absence of current which condition prevails when a block is already occupied by a train when the second train enters. On the train, the grid circuit of tube E is tuned to the first harmonic component, the grid circuit of tube E' is tuned to the third harmonic component and the grid circuit of tube E'' is tuned to the seventh harmonic component. Relays R, R' and R'' are each provided with two polarized armatures in place of one shown in other forms of the invention. When tubes E and E'' are influenced and tube E' is uninfluenced, (two blocks in advance unoccupied) then the maximum speed is permitted; with tubes E and E' influenced and tube E'' uninfluenced (second block in advance occupied) then the second speed is permitted; with tube E influenced and tubes E' and E'' uninfluenced (first block in advance occupied) the third speed will be permitted; and with tube E uninfluenced (block already occupied) the lowest speed only will be permitted.

I claim:

1. A trackway circuit system including: trackway elements, a power source to supply a single alternating current of a given frequency, connections between said power source and said trackway elements to establish, in said trackway elements, a current flow, means in said connections for establishing a wave form, for said current, having given pronounced harmonic components, and other means in said connections to determine if said given harmonic components are retained in the wave form of the current flowing in the trackway elements or if said given harmonic components are suppressed.

2. A trackway circuit system including: trackway elements divided into blocks, a power source to supply a single alternating current of a given frequency, connections between said power source and the trackway elements of a block to establish, in said trackway elements, a current flow, means in said connections to establish a wave form for said current having given pronounced harmonic components, other means in said connections to determine if said given harmonic components are retained in the wave form of the current flowing in the trackway elements of a block, or if said given harmonic components are suppressed, and a translating device responsive to traffic conditions of another block, to control the connections aforesaid.

3. A trackway circuit system including: trackway elements, a power source to supply

a single alternating current of a given frequency, said current having a plurality of pronounced components, and traffic controlled variable connections between the source and the trackway elements to selectively retain or suppress one or more of said components to thereby establish in the trackway elements a current having in response to different traffic conditions all or less than all of said components.

4. A trackway circuit system including: trackway elements arranged in blocks, a power source to supply a single alternating current of a given frequency, said current having a plurality of pronounced components, variable connections between the source and the trackway elements of a block to selectively retain or suppress one or more of said components to thereby establish in the trackway elements of a block a current having all or less than all of said components, and a translating device, responsive to traffic conditions of another block, to control the variable connections.

5. A trackway circuit system including: trackway elements arranged in blocks, a power source to supply a single alternating current of a given frequency, said current having a plurality of pronounced components, variable connections between the source and the trackway elements of a block to selectively retain or suppress one or more of said components to thereby establish in the trackway elements of a block a current having all or less than all of said components, and a translating device, responsive to the presence of current flow having one or more pronounced components in the trackway elements of another block, to control the variable connections.

6. A trackway circuit system including: a track composed of traffic rails, a power source to supply a single alternating current of a given frequency, said current having a plurality of pronounced components, and traffic-controlled variable connections between the source and the traffic rails to selectively retain or suppress one or more of said components to thereby establish in the traffic rails a current having in response to different traffic conditions all or less than all of said components.

7. A trackway circuit system including: a track composed of traffic rails and arranged in blocks, a power source to supply a single alternating current of a given frequency, said current having a plurality of pronounced components, variable connections between the source and the traffic rails of a block to selectively retain or suppress one or more of said components to thereby establish in the traffic rails of a block a current having all or less than all of said components, and a translating device, responsive to traffic conditions

of another block, to control the variable connections.

8. A trackway circuit system including: a track composed of traffic rails and arranged in blocks, a power source to supply a single alternating current of a given frequency, said current having a plurality of pronounced components, variable connections between the source and the traffic rails of a block to selectively retain or suppress one or more of said components to thereby establish in the traffic rails of a block a current having all or less than all of said components, and a translating device, responsive to the presence of current flow having one or more pronounced components in the traffic rails of another block, to control the variable connections.

9. A train control system including: trackway elements, a power source to supply a single alternating current of a given frequency, said current having a plurality of pronounced components, traffic-controlled variable connections between the source and the trackway elements to selectively retain or suppress one or more of said components to thereby establish in the trackway elements a current having in response to different traffic conditions all or less than all of said components, a vehicle, indicating means on the vehicle, and translating means on the vehicle selectively responsive to the influence of different components of the current in the trackway elements to thereby control the indicating means to give different indications corresponding to different traffic conditions.

10. A train control system including: trackway elements arranged in blocks, a power source to supply a single alternating current of a given frequency, said current having a plurality of pronounced components, variable connections between the source and the trackway elements of a block to selectively retain or suppress one or more of said components to thereby establish in the trackway elements of a block a current having all or less than all of said components, a translating device, responsive to traffic conditions of another block, to control the variable connections, a vehicle, indicating means on the vehicle, and translating means on the vehicle selectively responsive to the influence of different components of the current in the trackway elements to thereby control the indicating means to give different indications corresponding to different traffic conditions.

11. A train control system including: trackway elements arranged in blocks, a power source to supply a single alternating current of a given frequency, said current having a plurality of pronounced components, variable connections between the source and the trackway elements of a block to selectively retain or suppress one or more of said components to thereby establish in

the trackway elements of a block a current having all or less than all of said components, a translating device, responsive to the presence of current flow having one or more pronounced components in the trackway elements of another block, to control the variable connections, a vehicle, indicating means on the vehicle, and translating means on the vehicle selectively responsive to the influence of different components of the current in the trackway elements to thereby control the indicating means to give different indications corresponding to different traffic conditions.

12. A train control system including: a track composed of traffic rails, a power source to supply a single alternating current of a given frequency, said current having a plurality of pronounced components, and traffic-controlled variable connections between the source and the traffic rails to selectively retain or suppress one or more of said components to thereby establish in the traffic rails a current having in response to different traffic conditions all or less than all of said components, a vehicle, indicating means on the vehicle, and translating means on the vehicle selectively responsive to the influence of different components of the current in the traffic rails to thereby control the indicating means to give different indications corresponding to different traffic conditions.

13. A train control system including: a track composed of traffic rails and arranged in blocks, a power source to supply a single alternating current of a given frequency, said current having a plurality of pronounced components, variable connections between the source and the traffic rails of a block to selectively retain or suppress one or more of said components to thereby establish in the traffic rails of a block a current having all or less than all of said components, a translating device, responsive to traffic conditions of another block, to control the variable connections, a vehicle, indicating means on the vehicle, and translating means on the vehicle selectively responsive to the influence of different components of the current in the traffic rails to thereby control the indicating means to give different indications corresponding to different traffic conditions.

14. A train control system including: a track composed of traffic rails and arranged in blocks, a power source to supply a single alternating current of a given frequency, said current having a plurality of pronounced components, variable connections between the source and the traffic rails of a block to selectively retain or suppress one or more of said components to thereby establish in the traffic rails of a block a current having all or less than all of said components, a translating device, responsive to the presence of current flow having one or more pronounced components in the traffic rails of

another block, to control the variable connections, a vehicle, indicating means on the vehicle, and translating means on the vehicle selectively responsive to the influence of different

5 components of the current in the traffic rails to thereby control the indicating means to give different indications corresponding to different traffic conditions.

10 15. A train control system including: a track, a train, a single source of current, a trackway current modifying means, alternative paths to connect the current source to the track with the rails in series by way of the current modifying means or independently thereof, train-carried circuit means including two electron tubes one of which is responsive only to unmodified current and the other of which is responsive only to modified current in said track, and traffic-con-

20 trolled means to connect one or the other of said paths to the track.

16. A train control system including: a track, a train, a single source of current, trackway means to modify the form of the current, alternative paths to connect the current source to the track with the rails in series by way of the current modifying means or independently thereof, train-carried circuit means including two electron tubes one

25 30 of which is responsive only to unmodified current and the other of which is responsive only to modified current in said track, and traffic-controlled means to connect one or the other of said paths to the track.

35 Signed at New York city, in the county of New York, and State of New York this 14th day of February, 1927.
